UNITED STATES PATENT OFFICE.

WILLIAM J. FLICK, OF ALEXANDRIA, VIRGINIA.

PENCIL.

Application filed March 16, 1922. Serial No. 544,318.

To all whom it may concern:

Be it known that I, WILLIAM J. FLICK, a citizen of the United States, residing at Alexandria, in the county of Alexandria and State of Virginia, have invented certain new and useful Improvements in Pencils, of which the following is a specification.

This invention relates to improvements in pencils of that type in which a supply of leads is contained in a magazine within the barrel of the pencil and the leads are successively positioned for use and adapted to be fed from the pencil as they are worn down, the general object of the invention being to provide a construction in which the leads will be accurately positioned when renewal becomes necessary thus obviating the necessity of individually inserting the leads into the barrel of the pencil as in ordinary constructions.

Another object of the invention is to provide a pencil of the class mentioned above in which the magazine will not require to be filled with a supply of leads but on the other hand may in itself constitute an original container for the leads and be introduced directly into the barrel in place of an emptied magazine thus obviating the necessity of removing the leads from a separate container and arranging them in a permanent magazine.

In the accompanying drawings:

Figure 1 is an axial sectional view through a pencil embodying the invention;

Figure 2 is a side elevation of the member provided for feeding the lead follower of the pencil;

Figure 3 is a detail transverse sectional view on the line 3-3;

Figure 4 is a perspective view illustrating a modified form of the magazine;

Figure 5 is a similar view illustrating another modified form of magazine; and

Figure 6 is an end elevation of the body of the magazine shown in Figure 5.

The pencil embodies a barrel which is indicated in general by the numeral 1 and which may be in the nature of an integral or one piece tubular body or made up of inner and outer tubular sections but in any event is exteriorly reduced in diameter at one end as indicated by the numeral 2. Onto this end of the barrel 1 is fitted the cylindrical inner end portion 3 of a ferrule or tip which is indicated by the numeral 4

and which is tapered substantially to a point as is usual in the corresponding elements of other pencils of this type. The ferrule is provided interiorly with a tubular lead guide 5 fixed at one end within the minor end of the body of the ferrule and at its rear end within a disk 6 which is fixed in any suitable manner within the major end of the tapered portion of the ferrule body. 60 The ferrule is fitted frictionally onto the reduced end of the barrel 1 and may be removed when occasion requires as for example to permit of the removal of an emptied magazine and the substitution of a filled 70 magazine, and the tubular member 5 of the ferrule constitutes a guide for the active lead which has been fed from the magazine and which is indicated by the numeral 7.

Before proceeding to a description of the magazine which is employed in connection with the barrel, I will first describe the means provided for feeding the active lead from time to time as it is worn down. Various feeding means may be employed but the 80 one preferred and which is shown in the drawings comprises a follower which is indicated in general by the numeral 8 and which consists of a stem 9 having a lead engaging end 10 and having its other end laterally 85 turned or otherwise formed to provide a lug indicated by the numeral 11. The follower 8 is arranged slidably within a tube 12 which at one end is rotatably fitted within an opening 13 formed in a bushing 14 which is fixed 90 within the barrel 1 of the pencil at a point suitably spaced from the forward end of the said barrel, the said end of the tube 12 being preferably over turned or upset as at 15 so as to restrain it against longitudinal dis- 95 placement within the bushing 14 and yet permit of its rotation within said bushing.

The opposite end of the tube is fixed in any suitable manner in a head 16 which is provided with a reduced portion 17 rotatably fitting in the rear or butt end of the barrel 1, the said head 16 being preferably provided with a circumscribing bead 18 to abut against the said end of the barrel as clearly shown in Figure 1. If desired the 105 head 16 may be provided with an eraser tip indicated by the numeral 19, and in this event a cap 20 will be frictionally fitted onto the head 16 and will so firmly bind the head that it may serve as a means for rotating the 110 head and thus imparting rotating movement to the tube 12. The tube 12 is formed with

a longitudinally extending slot 21 through which the lug 11 projects, and the end of this lug projects into a helical slot 22 formed in the wall of a tubular feeding member 23 which rotatably receives the tube 12 and is anchored at its forward end in the bushing 14 so that it is fixed with relation to said bushing and to the barrel. It will now be evident that upon rotating the tube 12 through the instrumentality of the cap 20 or by holding the cap stationary and rotating the barrel, the lug 11 will be caused to travel in the helical slot 22 in the feeding tube 23 thus advancing or retracting the follower 8 and thus provide for adjustment of the active lead 7. Thus when the follower is advanced, the active lead will be fed through the tubular guide 5 and to project a suitable distance beyond the minor end of the ferrule 4 for writing purposes and after the lead has been exhausted and it is desired to bring a new lead into place from the magazine, the follower may be retracted by relatively rotating the barrel 1 and cap 20 in the manner previously explained.

The magazine of the pencil may assume various forms and be variously constructed but in general its exterior surface will describe substantially a cylinder and it will be of such dimensions as to adapt it to be removably and yet snugly fitted into the forward end of the barrel 1. The magazine, in that form of the invention illustrated in Figure 1 of the drawings is indicated in general by the numeral 24 and the same comprises a hollow cylindrical body 25 which as stated is exteriorly of a diameter to adapt it to be fitted snugly and yet removably within the forward end of the barrel, and when fitted into place its inner end will abut against the bushing 14, and its outer end portion will project a short distance beyond the end of the barrel and seat against the disk partition 6 within the ferrule 4 when the said ferrule is in place. In this manner the magazine is restrained against longitudinal displacement and held in properly centered position. In all forms of the invention the magazine is provided with a lead receiving chamber of substantially convolute form, and in providing this chamber, in the form of the invention shown in Figures 1 and 3, a wall member 26 of sheet metal is secured along one edge to the inner surface of the wall of the cylindrical body 25 of the magazine and extends inwardly and is turned back upon itself as at 27 so that on the whole it constitutes substantially a convolute partition wall having one edge united to the wall of the body 25 and the other edge spaced from the wall of said body. In this manner there is provided a channel or pocket 28 extending axially within the body 25 of the magazine and when the magazine is fitted into the barrel 1 of the

pencil, this channel will register at one end with the bore of the tube 12 and at its other end with the bore of the tube 5, and therefore a lead lodged within the channel or pocket will be in axial alignment with the bore of the tube 5 and, when the follower stem 9 is fed longitudinally through the said channel 28, the lead will be ejected from the channel and through the said tube 5. The space between the disconnected edge of the wall 26 and the surface of the wall of the body 25 is sufficient to permit the passage of a lead into the channel or pocket. In practice the magazines will be placed upon the market with a number of leads arranged within the convolute chamber of the magazine and one occupying said pocket or channel 28. After introduction of the magazine into the barrel of the pencil, the follower 9 having previously been retracted to the fullest extent, the cap 20 will be rotated so as to advance the follower stem 9 and thus feed the lead 7 which is at that time within the channel or pocket 28 outwardly through the tube 5 until it projects a suitable distance beyond the minor end of the ferrule 4. When this lead has been exhausted or substantially exhausted and it becomes necessary to bring a new lead into position for use, the barrel 1 is rotated with relation to the cap 20, or vice versa as may be preferred, until the follower stem 9 has been retracted to the fullest extent and has completely cleared the channel or pocket 28. The barrel of the pencil is then given a backward rotative movement so as to influence the next lead in position to roll over the edge of the partition wall 26 and drop into the channel or pocket 28. The follower stem 9 may then be adjusted so as to feed the newly positioned lead as occasion requires.

A modified form of magazine is illustrated in Figure 4 of the drawings and is indicated in general by the numeral 29 and the body of this magazine is preferably formed from a single integral blank of sheet metal rolled upon itself to provide a cylindrical wall 30 and a partition wall portion 31 which constitutes an integral continuation from one edge of the blank, the other edge of the blank meeting the fold or bend in the blank defining the juncture of the wall portions 30 and 31. In this figure also the numeral 32 indicates cap members which are adapted to be removably fitted onto the ends of the body 30, and similar members will be employed in connection with the magazine 24 previously described, the purpose of these cap members being to close the ends of the magazine and to retain the leads in place and thus adapt the magazine to serve initially as a dispensing container for the leads, both caps being removed and discarded at the time the magazine is to be fitted into the barrel of the pencil.

Figures 5 and 6 of the drawings illustrate another modified form of magazine indicated in general by the numeral 33 and the body of this magazine may be formed by first preparing a flattened tubular blank and then rolling the blank to convolute form so as to provide a convolute lead chamber as in the previously described forms and which chamber is indicated by the numeral 34. In this form also the ends of the body of the magazine are adapted to be closed by removable caps 35.

From the foregoing it will be understood that in all forms of the invention the magazine serves initially as a dispensing container for the leads and that after removal of the caps closing the ends of its body, it may be inserted into the barrel of the pencil and the ferrule 4 then fitted into place upon the barrel at which time the innermost end of the convolute lead chamber will be in alinement with the axis of the pencil barrel and one of the leads will be in position for ejection through the ferrule 4.

Having thus described the invention, what is claimed as new is:

1. In a pencil, a barrel having a magazine receiving chamber in its forward portion, a ferrule removably fitted to the said portion of the barrel and having a lead channel

in axial alinement with the barrel, a lead follower movable in alinement with the said channel, means for adjusting the follower, and a lead magazine removably disposed within the magazine receiving chamber of 35 the barrel and confined therewithin by the said ferrule, the said magazine having a convolute lead chamber the inner portion of the convolution of which is in alinement with the follower and the said channel. 40

2. In a pencil, a barrel having a magazine receiving chamber in its forward portion, a ferrule removably fitted to the said portion of the barrel and having a lead channel, a lead follower movable in alinement with 45 the said channel, means for adjusting the follower, and a lead magazine comprising a body having a convolute lead chamber the inner portion of the convolution of which is in alinement with the longitudinal axis 50 of the body, and removable means initially closing the ends of the body and the chamber therein whereby the magazine may initially constitute an original package for the supply of leads and, upon removal of the closure 55 means, may constitute an open ended magazine for removable insertion into the chamber in the barrel.

In testimony whereof I affix my signature.
WILLIAM J. FLICK. [L. S.]
